UNITED STATES PATENT OFFICE.

CAMILLE ST. HILAIRE, OF WILSON, MICHIGAN.

SELF-LEVELING AND ADJUSTABLE BERTH, &c., FOR SHIPS.

SPECIFICATION forming part of Letters Patent No. 694,214, dated February 25, 1902.

Application filed April 20, 1901. Serial No. 56,787. (No model.)

To all whom it may concern:

Be it known that I, CAMILLE ST. HILAIRE, a citizen of the United States, residing at Wilson, in the county of Menominee, State of Michigan, have invented certain new and useful Improvements in Preventers of Seasickness; and I do hereby declare the following to be a full, clear, and exact description of the invention, such as will enable others skilled in the art to which it appertains to make and use the same.

This invention relates to devices for preventing seasickness; and it has for its object to provide in connection with a vessel means for suspending the different articles of furniture so that they may not have the same movement as if they were fixed.

A further object of the invention is to provide a construction wherein the inclination of a chair, a bed, or a hammock may be varied to suit the pleasures of the occupant, additional objects and advantages of the invention being apparent from the following description.

In the drawings forming a portion of this specification, and in which like numerals of reference indicate similar parts in the several views, Figure 1 is a perspective view showing a chair suspended from its hanger. Fig. 2 is a side elevation of the construction shown in Fig. 1 and showing the chair in its tilted position. Fig. 3 is a side elevation showing a hammock suspended from the style of hanger shown in Fig. 1. Fig. 4 is a top plan view showing a bed suspended from a hanger such as shown in Fig. 1, the bed-clothing being removed to show the means for shifting the longitudinal and transverse inclinations of the bed. Fig. 5 is a perspective view showing a different form of hanger and with a bed suspended therefrom.

Referring now to the drawings, and more particularly to Figs. 1 and 2, there is shown a chair 10, to which are secured the ends of the arms 11 of a spider-frame, said arms having connecting-webs 12, to which is attached a plate 13, having spaced hooks 14. A hanger is provided and consists of a plate 15, having depending brackets 16, in which is pivotally mounted a horizontal shaft 18, having a depending central portion 19, through which is

passed a transverse rod 20, projecting at both sides thereof. The rod 20 is adapted for engagement by the spaced hooks on the plate of the spider-frame that is connected to the chair, so that the chair may have both forward and lateral swinging movement.

The hooks above referred to are adapted for limited sliding movement on the bar with which they are engaged, and upon reference to Fig. 2 of the drawings it will be noted that if the hooks be shifted to one limit of their movement the chair will assume a position which is inclined at an angle to the position assumed when the hooks are at the opposite limit of their movement. In this way the inclination of the chair may be varied to suit the pleasure of the occupant.

In Fig. 3 of the drawings there is shown a spider frame 20', having a hook-plate 21, provided with spaced hooks 22 for engagement with the bar of the suspending device or hanger, and at the lower ends of the arms of this frame are hooks 23. A hammock 24 has rollers 25 and 26 engaged with its ends and which rollers are provided with trunnions for engagement with the hooks of the frame to hold the hammock in operative position. The trunnions of one roller are flattened and when engaged with their hooks and held against rotation one end of the hammock may be wound upon this roller to increase the tension of the hammock, and the squared trunnions may be then engaged with the hooks to prevent unwinding. The hammock, as will be readily understood, is thus adapted for lateral and longitudinal swinging movement, while the inclination of the hammock in a longitudinal plane may be varied by shifting the hooks of the spider-frame along the bar of the hanger.

In Figs. 4 and 5 of the drawings a spider-frame 30 is shown similar to that shown in Fig. 3 and having a plate 31 at its central portion provided with spaced hooks 32 for engagement over the bar 33 of the hanger. The ends of the arms of the spider-frame are attached to the corners of the bed-frame, and when the device is hung in its normal position this bed-frame lies horizontally.

In the bed-frame is disposed the usual mattress. A rod 35 is disposed transversely of

the bed and connected at its ends with the mattress-frame 36, and on this rod is slidably disposed a weight 36', having cords 37 and 38 attached thereto and which cords are taken through guides and depend from the same side of the bed, these guides (shown at 39 and 40) being so disposed that if one cord is pulled the weight will move to one end of the rod and if the other cord is pulled the weight will move to the other end of the rod. Thus if two persons occupy the bed and one is lighter than the other the weight may be shifted to compensate for the difference between the weights of the occupants, so that the bed may lie horizontal.

In order that the inclination of the bed may be varied to raise and lower the head thereof, a second rod 41 is provided and is connected at one end to the lower end of the bed-frame or foot of the bed-frame or mattress-frame, and the other end thereof is attached to a transverse bar 43, secured to the sides of the mattress-frame. On the bar 41 is slidably disposed a weight 44, which when moved to the foot end of the bar acts to depress the foot of the bed and raise the head thereof. When the weight is moved in the opposite direction, the head of the bed sinks and the foot thereof rises. Cords 45 and 46 are attached to the weight, and by operation of these cords, which are passed through suitable guides, the weight may be shifted to vary the inclination of the bed.

A second form of hanger is provided for the bed and consists of a plate 50, having depending spaced brackets 51, in which are rotatably mounted the trunnions 52 of a block 53, having additional trunnions 54 at right angles to the first-named trunnions. The hooks of the hanging frame of the bed are engaged with these second trunnions and by contact with the body of the block are prevented from movement longitudinally of the trunnions.

It will be understood that other articles of furniture may be similarly suspended.

What is claimed is—

1. A device of the class described comprising a hanger including depending ears having bearings therein, a shaft mounted in the bearings, a second shaft carried by the first shaft, and lying at right angles thereto, a plate having hooks engaged slidably and pivotally with the second shaft, a spider connected with the hook-plate and comprising two pairs of arms having terminal hooks, a roller having trunnions engaged with the hooks of one pair of arms, a second roller having angular trunnions engaged removably with the hooks of the other pair of arms to be held against rotation thereby, and a fabric connecting the rollers, whereby the tension of the fabric may be adjusted.

2. The combination with a vessel of a pivoted shaft, a frame pivotally connected with the shaft for movement in a plane at right angles to the pivotal movement of the shaft, said frame being shiftable with respect to the shaft in a plane at right angles thereto to shift its center of gravity, and a passenger-receptacle carried by the frame.

3. A device of the class described comprising a hanger including a plate having depending spaced ears provided with bearings, a shaft mounted in the bearings, a second shaft carried by the first shaft at right angles thereto, a plate having spaced upwardly-directed hooks engaged slidably and pivotally with the second shaft, a spider connected to the plate and a passenger-receptacle attached to the spider.

In testimony whereof I hereunto sign my name, in the presence of two subscribing witnesses, on the 25th day of February, 1901.

CAMILLE ST. HILAIRE.
